ATTORNEY.

UNITED STATES PATENT OFFICE.

JOHN W. NEUMANN, OF LOUISVILLE, KENTUCKY.

PACKING-BOX.

SPECIFICATION forming part of Letters Patent No. 595,726, dated December 21, 1897.

Application filed July 16, 1897. Serial No. 644,817. (No model.)

To all whom it may concern:

Be it known that I, JOHN W. NEUMANN, a citizen of the United States, residing at Louisville, in the county of Jefferson and State of Kentucky, have invented a new and useful 5 Packing Box or Crate, of which the following is a specification.

The objects of my invention are, first, lightness; second, strength; third, cheapness of 10 manufacture; fourth, ease and quickness in closing and opening, and, fifth, security. I attain these objects by the device illustrated in the accompanying drawings, in which—

Figure 1 is a vertical section of the box 15 closed with one edge left unfolded; Fig. 2, a projection of a portion of the metal forming the sides, and Fig. 3 the edge of the metal siding.

Similar figures refer to similar parts through 20 out the several views.

1 is the cover of the box, 2 is the bottom, and 3 the sides.

The top 1 and bottom 2 are flat boards of 25 wood or other soft material, and the sides 3 of sheet metal. The sheet-metal siding is corrugated, as shown in Figs. 2 and 3. At the corners 4 the corrugated siding is notched at such an angle as to form a close joint when folded over on the cover and bottom. At 6

30 a crease is formed across the corrugations the entire length of the siding to facilitate folding over and to determine the position of the edges of the box. The ends of the siding may

be joined by riveting or soldering, but preferably by folding. The corrugations in the 35 sheet-metal siding serve to stiffen it and to form a serrated edge which, when pressed into the end pieces, bites in, as shown at 7, and prevents the portion 6 to 7 from unfolding. Nailing is thus rendered unnecessary 40 and closing the box much facilitated.

To open the box, a suitable cutter is inserted at one of the corners 4, and the edge 6 cut around so as to remove the portions 6 to 7, when the cover will easily slip out, leaving 45 a clean opening. This feature also renders the box non-refillable.

The entire box may be made of corrugated sheet metal with a groove pressed into the end pieces at 7 to receive the edge of the 50 siding.

What I claim as my invention is—

In a tobacco-box, the combination of sides 3, made of sheet metal or other material corrugated vertically, top and bottom pieces 1 55 and 2, the sheet siding creased at 6, 6 to each edge to form a locking device to lock the top and bottom pieces 1 and 2 in place by pressing the serrations formed by the corrugated edges into the surface of said top and bottom 60 pieces, all substantially as and for the purpose specified.

JOHN W. NEUMANN.
